Radio Corporation of America, a corporation
of Delaware

Application August 25, 1943, Serial No. 499,905

10 Claims. (Cl. 179—171.5)

1

This application concerns a new and improved voltage phase shifting system. The system of this invention is of use as a static phase shifter and as the modulator in a phase or frequency modulation system wherein the phase or frequency shift is in accordance with signals.

An object of the invention is to provide a modulator capable of greater phase deviation than is attainable in known systems, and hence to make it possible to use in the system fewer multiplier stages.

Where a large amount of frequency multiplication is used the final output has in addition to the main frequency selected for use a large number of harmonics of the oscillator frequency. An advantage of my system is the reduction of harmonics in the output of the system by producing in the modulator a greater phase deviation so that less multiplication is required in the following stages.

Another object of this invention is to provide in a modulation system of this type a greater phase deviation of wave energy in accordance with signals and to accomplish this object without causing appreciable amplitude modulation of the wave energy. This is accomplished in my system by the use of a differential modulation system wherein the amplitude variations are opposed to cancel.

If alternating voltage is applied to a reactance, a second reactance of opposite sign and half the value of the first reactance and a resistance in series a voltage is derived across the second reactance and resistance of an amplitude equal to the amplitude of the first voltage and of a phase which with respect to the phase of the first voltage depends on the size of the resistance. By varying the resistance the phase of the second voltage changes and a phase change of about 180° is obtainable. I make use of this principle to provide a static phase changer or a wave length modulator in which case the resistance is a tube.

If a second resistance of opposite sign is put in parallel with the first resistance the phase shift is doubled. To explain briefly how I accomplish this assume the first resistance is positive and comprises a tube. I place a second tube in parallel thereto and apply the alternating voltage to its grid in phase opposition with respect to the phase of the voltage on the first tube so that the second tube appears as a negative resistance. These tubes are now differentially modulated and the phase is shifted about twice as much as in the single tube case, i. e., about 360 degrees.

The principle employed above applies to other phase modulators wherein the phase shift is ob-

2

tained by varying a tube resistance. In these arrangements I couple a second tube resistance in parallel with the first tube resistance and arrange the circuits so that one of the tubes acts like a positive resistance while the second tube acts like a negative resistance, the tubes being differentially modulated.

It will be at once apparent, that, as in the single tube arrangements, the phase only of the voltage is varied, the amplitude remaining constant.

An advantage which flows from the use of my improved arrangement using two tubes is that less multiplication is necessary to get the final phase shift desired and this in turn reduces the harmonic components in the final output which results from the use of a large amount of multiplication.

In describing my invention reference will be made to the attached drawings wherein Figs. 1 and 3 illustrate diagrammatically simple phase shifting circuits and are used to explain the principle involved in my improved phase shifters and modulators. Figs. 2, 3a, 4 and 5 illustrate modifications of my improved phase shifter and timing modulation system as described briefly above; while Figures 2a, 2b, 2c, 2d, 2e, 3b and 3c are basic circuits or graphs illustrating the operation of the several modifications shown in the other figures.

In Fig. 1, an alternating voltage e_1 of carrier frequency is applied across $2Z$ and the tube T cathode. $2Z$ is a reactance which may be capacity or inductive in nature, while $-Z$ is a reactance of opposite sign. The magnitude of $2Z$ is twice that of $-Z$. T which represents a variable resistance, is an electron discharge device having its anode and control grid excited by voltages of the same phase and its cathode connected to the other side of the input circuit. e_2 is the phase shifted or phase modulated voltage derived from the system. In the sake of simplicity, direct current circuit have been omitted in this figure, but it will be understood that the plate of the tube T may be charged through a radio frequency choke connected thereto, and to a source of direct current, while the grid may likewise be biased through a radio frequency choke, and modulating potentials may be applied through this choke to the said grid.

Fig. 1 shows a simple phase changer or modulator. Since the alternating current plate and grid voltages on the tube T are equal the admittance of the tube is readily seen to be

$$Y = \frac{ip}{ep} = g + \frac{1}{R} = g \left(1 + \frac{1}{u} \right) \quad (1)$$

(where g , R , and u are the transconductance,

plate resistance, and amplification factor of the tube respectively). The ratio of output to input voltage for Fig. 1 is seen to be

$$\frac{e_2}{e_1} = \frac{\frac{1}{Y} - Z}{2Z - Z + \frac{1}{Y}} = \frac{1 - YZ}{1 + YZ} = \frac{1 - gZ \left(1 + \frac{1}{u}\right)}{1 + gZ \left(1 + \frac{1}{u}\right)} \quad (2)$$

If Z is taken as a reactance we see that e_2 is shifted in phase from e_1 but that both have the same amplitude. Also, if the magnitude of g is varied (by varying the grid bias on the tube, for instance) the phase shift between e_2 and e_1 will vary. If audio voltages are applied to the grid of the tube the carrier voltage e_2 will be phase modulated in accordance with the audio voltage.

The variation in g will, at most, be from zero to infinity. The variation in phase of e_2 will, therefore, at most, be from zero to 180 degrees, or $\pm 90^\circ$. If g , however, could be varied from minus infinity through zero to plus infinity the phase would be varied from minus 180° to plus 180° . This can be accomplished by paralleling the tube in Fig. 1 by another tube whose grid voltage is 180° out of phase with its plate voltage. Figs. 2, 3a, 4 and 5 show circuits which accomplish this. In these arrangements the control voltages on the tube electrodes must be pushpull also.

In the actual choice of circuit elements used in these two tube modifications care must be taken that they are not such as will make the circuit oscillate.

In Fig. 2 the direct current sources have again been omitted in the sake of simplicity as have the cathode heating circuits. A second tube T_1 is coupled in parallel with tube T and the control grid G_1 thereof excited in phase opposition by the radio frequency oscillations. The plates and grids are supplied with direct current potentials by resistances 20 and 22 of the proper value, resistances being preferable to choke coils in these systems.

In the arrangement of Fig. 2, $2Z$ is, for example, taken as a capacity C and $-Z$ is taken as an inductance L . C_1 , L_1 , L_2 are made small so that the grid G_1 of tube T_1 is excited by a voltage substantially 180° out of phase with respect to the voltage on the anode of this tube T_1 . CC is a coupling condenser and such that the phase of the voltage of the grid G of tube T is substantially the same as the phase of the voltage on the anode of this tube T and the anode of tube T_1 . This condenser CC keeps the plate potential from reaching the grid G while condenser C_1 in like manner keeps the direct current potential from reaching the grid G_1 of tube T_1 . The voltages on the grids are made equal by properly dimensioning L_1 , L_2 , C_1 , CC and 20.

In this embodiment the modulating potentials are applied in pushpull relation to the control grids G and G_1 of the tubes by a transformer. The total phase shift obtainable in this arrangement is about twice the phase shift obtainable in the single tube arrangement of Fig. 1 or about 360 degrees.

The modulation transformer 18 has its primary supplied with modulation currents and the terminals of its secondary winding coupled to the grids G and G_1 by way of L_2 and resistance 20 and a point on its secondary winding connected through a bias source to the cathodes of the tubes. The plates are supplied with potential through a resistance 22. Resistances 20 and 22 are large enough not to shunt out the radio frequency alter-

nating current. RF bi-pass condensers BP are connected between resistances 20 and 22 and the cathodes and between the lower end of L_2 and the cathode of tube T_1 .

Since in my improved system one tube acts as a positive resistance and the other as a negative resistance the problem of regeneration in the circuits and generation of oscillations at some frequency must be considered. The analysis may be carried out by applying the Nyquist regeneration theory as described in the Bell Telephone Technical Journal, vol. 11, page 126.

LC ($-Z$ and $2Z$) resonates at $\sqrt{2} f$ (f =carrier frequency). L_1 , L_2 , and C_1 are proportioned to make the grid voltages on G and G_1 equal. The resonance of L_1 , L_2 , C_1 is greater than f . L_1 , L_2 , and

$$\frac{1}{C_1}$$

20 are large compared to L and $\frac{1}{C}$.

For purposes of analysing for oscillations tube T may be neglected and we may therefore consider the circuit of Fig. 2a.

25 Two cases are possible;

(I) The resonance of L_1 , L_2 , C_1 is below that of LC

(II) The resonance of L_1 , L_2 , C_1 is above that of LC

30 For case I:

The reactance seen by the plate of the tube is shown in Fig. 2b. The locus of the vector e/e_1 is shown in Fig. 2c. Since below f_1 , e_2 leads e by 180° , at f_1 , e_2 leads e by 90° ; above f_1 , e_2 is in phase with e ; the locus of the vector

$$\frac{e_2}{e_1}$$

40 is shown in Fig. 2d. The locus cannot include the point 1, 0 and therefore where the resonance of L_1 , L_2 , C_1 is below that of LC this circuit cannot oscillate.

45 For case II:

By the same sort of an argument the locus of the vector

$$\frac{e_2}{e_1}$$

50 is as shown in Fig. 2e. The locus can enclose the point 1, 0 and therefore under case II the circuit can oscillate.

Thus it is seen that the circuit illustrated in Fig. 2 will be stable in operation if the resonance of L_1 , L_2 , C_1 is below that of LC , and will provide a total phase change of about 360° . The phase of e_2 may be displaced a fixed amount by properly biasing the tubes to thereby change their impedance. If modulating potentials are applied in pushpull the system becomes a phase modulator.

The principle applied above to obtain a large amount of phase change or modulation may also be applied to phase changers of the type shown in Fig. 3.

In Roberts U. S. Patent No. 2,143,386, dated January 10, 1939, it is shown that the network of Fig. 3 has the property of shifting the phase of a voltage e_1 applied to the input thereof without changing its amplitude, so that at the output a voltage e_2 may be derived which is of the same amplitude as the voltage e_1 . The equation of operation is

$$\frac{e_2}{e_1} = \frac{1 - Zg}{1 + Zg} \quad (3)$$

where Z is a pure reactance and g is the transconductance of the tube. Phase modulation may be accomplished by applying audio voltages to the grid. These audio voltages serve to vary the transconductance g at audio rates and cause e_2 to be phase modulated with respect to e_1 .

It can be seen that with this circuit g can at most be varied from zero to infinity and hence the phase can at most be modulated about 180° peak to peak.

In my invention as illustrated in Fig. 3a, I have added another tube T_1 with its plate 40 and cathode 42 in parallel with the plate 44 and cathode 46 of tube T. Condensers C_5 and C_6 are equal. The grid G of tube T is tapped between these condensers so that it gets a voltage of a first phase not necessarily the same as the phase of e_1 . The grid G_1 of tube T_1 gets its radio frequency voltage through C_7 and L_7 and this voltage is shifted by C_7 and L_7 nearly 180° with respect to the voltage of said first phase on the grid G. The circuit constants are made such that the grid voltages are of like magnitude.

The effect of T is as given by Equation No. 3 above. The effect of T_1 considered alone is given by the Equation No. 3 above except that when considering tube T_1 , g is now a negative quantity. By modulating the grids G and G_1 of tubes T and T_1 out of phase with respect to each other, phase shifts of about 360° peak to peak are obtained. The modulation may be applied by means of a transformer 18 the secondary winding of which couples the control grids in push-pull relation as in Fig. 2. A point on the secondary winding of the transformer 18 is coupled to the cathodes through a biasing source 51. Resistance 20 in the modulation circuit lead to grid G has substantially the same purpose as resistance 20 of Fig. 2. Inductance L_1 also completes the modulation circuit to grid G_1 as does L_2 in Fig. 2. The grids of T and T_1 may be biased by this source to cutoff, in which case the operation will be equivalent to class B or this source may be such as to bias the grids with respect to the cathodes by any voltage less than that at which cutoff is attained and then operation will be equivalent to class A, or class AB.

The phase modulated output e_2 is derived from the line, i. e., across the impedance of T_1 50 and this output may be supplied to additional circuits of apparatus such as, for example, frequency multipliers, wave amplifiers, etc.

In this arrangement precautions must likewise be taken to assume that the circuit does not become unstable and oscillate at some other frequency. The u_s diagram, see Fig. 3c, for the circuit above, simplified as shown in Fig. 3b, does not enclose the point 1, 0 and hence does not oscillate.

In a modification illustrated in Fig. 4 the grid G_1 is coupled to the points between the reactances and this point is also coupled by phase reversing coupled inductances 50 to the control grid G_1 to apply to said control grid a voltage opposed in phase with respect to the voltage on the control grid G.

In the modification of Fig. 5, one of the coupling inductances is in the cathode circuit of tube T and the other as in Fig. 4, is coupled to the grid G_1 . The modulation circuit is substantially as in Figs. 2 and 3a, but now includes a resistance 22' between the transformer 18 secondary winding and grid G_1 . A direct current blocking and radio frequency coupling condenser 75

BC is in series between the secondary winding of radio frequency transformer 50' and the grid G_1 .

Both of these modifications operate as described above in connection with Figs. 3 and 4a.

What I claim is:

1. In a circuit of the class described, two conductors each having input and output terminals, means for impressing voltages of carrier wave frequency on said input terminals, reactance in one of said conductors, a first variable resistance of positive sign connected across said conductors at their output terminals, said connection including a second reactance, and said first reactance between said resistance and the input terminal of said one conductor, a second variable resistance of negative sign connected in parallel to said first resistance and connections for varying said resistances differentially in accordance with control potentials to correspondingly vary the voltages at said output terminals.
2. In a system of the class described, a two-conductor line having input and output terminals, means for applying voltages of carrier frequency on said input terminals, reactance in one of said conductors, a first electron discharge device having the impedance between its output electrodes connected across said line at its output terminals, said connection including said first reactance, and a second reactance between said impedance and one of said input terminals, said device having a control electrode, a second electron discharge device having a control electrode and having the impedance between its output electrodes connected in parallel to the impedance between the output electrodes of said first device, circuits for applying voltages of said carrier frequency substantially in phase-opposed relation to the control electrodes of said devices, where 25 by one thereof operates as a negative impedance, while the other thereof operates as a positive impedance, and connections for varying the impedances of said devices differentially in accordance with control potentials to correspondingly vary the phase of the voltages at said output terminals.
3. In a system of the class described, a two-conductor line having input and output terminals, means for applying voltages of carrier frequency to said input terminals, two similar reactances in one of said conductors, a first electron discharge device having the impedance between its output electrodes connected across said line at its output terminals, said device having a control electrode, a second electron discharge device having a control electrode and having the impedance between its output electrodes connected in parallel to the impedance between the output electrodes of said first device, a coupling between 30 adjacent terminals of said two reactances and the control electrodes of said devices for applying voltages of said carrier frequency substantially in phase-opposed relation to the control electrodes of said devices, whereby one thereof operates as a negative impedance, while the other thereof operates as a positive impedance, and connections for varying the impedances of said devices differentially in accordance with control potentials to correspondingly vary the phase of the voltages at said output terminals.
4. In a timing modulation system, a pair of electron discharge tubes each having an anode and a control grid, a first reactance, and a second reactance of like sign and of substantially 35 the same magnitude as said first reactance in

series, connections for impressing voltages the timing of which is to be modulated between said series circuit and a point of low potential, connections coupling the output impedances of said tubes in parallel between said reactances and said point of low potential, a coupling between adjacent terminals of said reactances and the control grid of one of said tubes, a coupling between said last named coupling and the control electrode of the other tube, phase reversing means in said last named coupling and circuits for modulating the impedances of said tubes differentially in accordance with signals whereby voltage of the carrier wave frequency modulated as to timing in accordance with said signals appear at the anodes of said devices.

5. In a timing modulation system, a pair of electron discharge devices each having an anode, a cathode and a control electrode, a first reactance, and a second reactance of like sign and of substantially the same magnitude as said first reactance in a series connection, connections for impressing alternating voltages the phase of which is to be modulated between one terminal of said series circuit and a point of low alternating current potential, connections coupling the impedances between the anodes and cathodes of said devices in parallel between the other terminal of said series connection and said point of low alternating current potential, high frequency circuits for impressing said carrier frequency voltages substantially in phase-opposed relation on the control electrodes of said devices, and circuits for modulating the impedances of said devices differentially in accordance with signals whereby voltage of the carrier wave frequency modulated as to timing in accordance with said signals appear between said other terminal of said series connection and said point of low alternating current.

6. In a timing modulation system, a pair of electron discharge devices each having an anode, a cathode and a control electrode, a first reactance, and a second reactance of like sign and of substantially the same magnitude as said first reactance in a series connection, connections for impressing alternating voltages the phase of which is to be modulated between said series circuit and a point of low alternating current potential, connections coupling the impedance between the anode and cathode of said devices in parallel between one end of said series connection and said point of low alternating current potential, a coupling between the control electrode of said devices and a point intermediate said reactances and connections for modulating the impedances of said devices differentially in accordance with signals whereby voltage of the carrier wave frequency modulated as to timing in accordance with said signals at the anodes of said devices.

7. In a phase modulation system, a pair of electron discharge devices each having an anode, a cathode and a control electrode, a first reactance, and a second reactance of like sign and of substantially the same magnitude as said first reactance in a series connection, connections for impressing alternating voltages the phase of which is to be modulated between said series circuit and a point of low alternating current potential, connections coupling the impedances between the anodes and cathodes of said devices in parallel between one end of said series connection and said point of low alternating current potential, a coupling between the control elec-

trode of one device and a point intermediate said reactances, a phase reversing coupling between said last coupling and the control electrode of the other device, and connections for modulating the impedances of said devices differentially in accordance with signals whereby voltage of the carrier wave frequency modulated in phase in accordance with said signals appears across the impedances between the anodes and cathodes of said devices.

8. In a phase modulation system, a pair of electron discharge tubes each having an anode, a cathode and a control electrode, a first reactance, and a second reactance of like sign and of substantially the same magnitude as said first reactance in a series connection, connections for impressing alternating voltages the phase of which is to be modulated between said series circuit and a point of low alternating current potential, connections coupling the impedances between the anodes and cathodes of said tubes in parallel between one terminal of said series connection and said point of low alternating potential, a coupling between a point intermediate said reactances and the control electrode of one tube, a phase reversing coupling the cathode of said one tube to the control electrode of the other tube, and connections for modulating the impedances of said tubes differentially in accordance with signals whereby voltage of the carrier wave frequency modulated in phase in accordance with said signals appears across said tube output impedances.

9. In a phase modulation system, a pair of electron discharge devices each having an anode, a cathode and a control electrode, a first condenser, and a second condenser of substantially the same magnitude as said first condenser in a series connection, connections for impressing alternating voltages the phase of which is to be modulated between one end of said series connection and a point of low alternating current potential, connections coupling the impedances between the anodes and cathodes of said devices in parallel between the other end of said series connection and said point of low alternating current potential, a coupling between the control electrode of one device and a point intermediate said condenser, a phase reversing coupling between said last coupling and the control electrode of the other device, and connections for modulating the impedances of said devices differentially in accordance with signals whereby voltage of the carrier wave frequency modulated in phase in accordance with said signals appears across the impedances between the anodes and cathodes of said devices.

10. In a phase modulation system, a pair of electron discharge tubes each having an anode, a cathode and a control electrode, a first inductance, and a second inductance of substantially the same magnitude as said first inductance in a series connection, connections for impressing alternating voltages the phase of which is to be modulated between one end of said series connection and a point of low alternating current potential, connections coupling the impedances between the anodes and cathodes of said tubes in parallel between the other terminal of said series connection and said point of low alternating potential, a coupling between a point intermediate said inductances and the control electrode of one tube, a phase reversing coupling between said first mentioned coupling and the

control electrode of the other tube, and connections for modulating the impedances of said tubes differentially in accordance with signals whereby voltage of the carrier wave frequency modulated in phase in accordance with said signals appears across said tube output impedances.
